THOMAS J. DOWD.

INVENTOR

BY *Victor J. Evans*

ATTORNEY

D. W. Dowd Jr.
WITNESS:

UNITED STATES PATENT OFFICE.

THOMAS J. DOWD, OF BRONX, NEW YORK.

CINDER ARRESTER.

Application filed August 5, 1927. Serial No. 210,951.

This invention relates to improvements in cinder arresters for coal burning locomotives.

The primary object of the invention is to provide an attachment for locomotives for deflecting the cinders as they pass out through the stack to prevent them from entering the cars behind and for preventing hot cinders and sparks from causing damage by fire to property along railroads.

Another object of the invention is to provide a cinder arrester including a hood mounted above and behind the smoke stack of a locomotive for trapping the cinders as they pass from the smoke stack, there being an opening in the rear wall of the hood for the escape of the trapped cinders and a baffle member partially encircling the boiler of the locomotive rearward of the hood to deflect the cinders to cause them to drop to the road bed.

A further object is the provision of a cinder arrester which is simple in construction and which may be applied to locomotives now in use without requiring any change in construction thereof.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a side elevation of a locomotive with my improved cinder arrester thereon.

Figure 2 is an enlarged vertical sectional view through the cinder arrester.

Figure 3 is a vertical transverse sectional view on the line 3—3 of Figure 2.

Figure 4 is a detail perspective view of the baffle member.

Figure 5 is a detail perspective view of the hood.

Referring more particularly to the drawing, the reference numeral 10 designates a locomotive of the coal burning type which includes the usual boiler 11 and smoke stack 12. My improved cinder arrester includes two elements, namely a hood 13 and a baffle member 14.

The hood 13 comprises an annular ring 15 which fits snugly about the smoke stack 12 and which is secured thereto in any suitable manner such as by bolts or rivets 15'. Formed integral with the ring 15 is a casing 16 which

includes vertical walls 17 and a horizontal top wall 18, the said top wall overlying the top of the stack 12 to deflect the cinders as they escape therefrom. The rear side of wall 17 is spaced from the ring and stack to allow the accumulation of the cinders in the space 19 therebetween and from which they escape through an opening 20 in the rear side wall. The bottom edge of the hood member is shaped to fit snugly against the boiler 11 but has a portion of the edge spaced from the boiler to form the opening 20.

The baffle member 14 comprises a segmental vertical wall 21 from which an attaching flange 22 extends and lies flat against the outside of the boiler 11. Bolts or rivets 23 pass through the flange 22 and boiler for securing the baffle member thereto. A baffle flange or horizontal wall 24 extends from the vertical wall 21 at a right angle thereto and is curved to lie in even spaced relation to the boiler. The ends of the baffle member terminate below the horizontal axis of the boiler to prevent any possibility of the cinders escaping to the rear.

In practice, the sparks and cinders from the engine or locomotive pass out of the smoke stack and are trapped within the hood 13 which has an open front 25 for the escape of smoke and for creating a draft through the hood and opening 20 when the locomotive is in motion. The cinders pass through the opening 20 and are deflected by the walls 21 and 24 of the baffle member so as to drop downward upon the road bed. It will be appreciated that my invention will eliminate the inconvenience of cinders entering the passenger cars of a train and will also reduce the fire hazard along a railroad, caused by sparks from the engine alighting upon adjacent property.

What is claimed as new is:—

1. A cinder arrester for locomotives comprising a hood open at its front, an attaching collar spaced from the rear wall of said hood and adapted to be fitted over a smoke stack, the rear lower edge of said hood being shaped to lie in spaced relation with respect to the boiler of a locomotive when said hood is in a seated position thereon to provide a restricted cinder outlet.

2. A cinder arrester for locomotives comprising a hood open at its front, an attaching collar spaced from the rear wall of said

hood and adapted to be fitted over a smoke stack, the rear lower edge of said hood being shaped to lie in spaced relation with respect to the boiler of a locomotive when said hood is in a seated position thereon to provide a restricted cinder outlet, and an arcuate baffle member adapted to be fixedly mounted on

the boiler of a locomotive to surround the top and sides thereof rearward of said hood to deflect any cinders passing out through the cinder outlet therein. 10

In testimony whereof I have affixed my signature.

THOMAS J. DOWD.
